BED AND CYLINDER ADDRESS PRINTING
MACHINEWalter T. Gollwitzer, Euclid, Ohio, assignor
to Addressograph - Multigraph Corporation,
Cleveland, Ohio, a corporation of Delaware

Application June 14, 1946, Serial No. 676,667

2 Claims. (Cl. 101—56)

1

This invention relates to a printing machine and particularly to platen mechanism adapted to be used in printing machines. More particularly the invention pertains to platen mechanism for use in selective printing machines of the character wherein printing devices, which may include address plates and the like, are passed in series through a printing position for cooperation with the platen mechanism.

Machines of the character mentioned above are used in the preparation of business instruments such as utility bills, dividend checks, premium notices and the like, as well as for printing names, addresses and like changeable data on letters, publications, and the like. Commonly, in the past, it has been the practice to use a reciprocating platen at the printing position which presses the sheet or other article being printed into contact with the printing member which, as suggested above, may be a printing device bearing an address plate. An inked ribbon or equivalent inking device is commonly interposed between the printing member and the article being printed and the platen pressing against the rear face of the article causes an impression to be made from the printing member through the ribbon onto the face of such article.

Printing devices of the character mentioned above commonly include a group of raised printing characters, for example, characters embossed on a sheet metal plate into a raised plane which constitutes the printing surface. The effective area of the printing surface may vary considerably, depending, for example, upon the number of letters or characters in the name, address, or other data carried by the printing member. In the prior art where reciprocating platens have been used to press articles being printed against such raised type characters it has been difficult to secure uniform impressions because of the wide variance in printing area. In my copending application, Serial No. 416,548, filed October 25, 1941, now issued as Patent No. 2,410,935, patented November 12, 1946, I have disclosed a hydraulically operated reciprocating platen mechanism which represents an improvement over prior platen structures in that the impression stroke is accurately controlled so that a deeper imprint is not produced from a printing member having few printing characters thereon than in the case of a printing member having a large number of printing characters. As described in such application, this result is secured by using a very rigid frame structure to support the reciprocating platen and rigid stop means for limiting its

2

movement. The use of rigid and heavy frame members is made necessary by the fact that pressures required for imprinting by reciprocating action are very high. Hence, the frame members and reciprocating parts must be massive to secure the result mentioned above.

It is an object of my present invention to replace the reciprocating platen structure of my aforesaid copending application by a roller platen mechanism, which will produce uniform impressions from various printing devices having variable effective printing areas, without requiring the use of heavy and massive structural elements. This is accomplished by using a travelling roller which produces its impression by a substantially shifting line contact, thereby requiring much less application of force and making it possible to reduce substantially the rigidity and mass of various structural elements without sacrificing accuracy and uniformity of impression.

A further object of my invention is to operate a shifting roller platen by simple hydraulic means.

Another object is to combine a platen of the roller type, for producing the main impressions at a printing station, with an auxiliary platen element for printing auxiliary data at the printing station.

An additional object is to mount a roller platen, as well as an auxiliary platen, in a supporting frame work designed to afford adequate rigidity and accuracy of impression without the employment of particularly heavy structural elements.

A still further object of my invention is to mount a platen roller in a travelling carriage, in combination with mechanism for raising and lowering such roller from and to impression position respectively, which mechanism operates in accordance with and under control of the shifting movement of the carriage which supports the platen roller.

Other and further objects of the present invention will be apparent from the following description and claims and are illustrated in the accompanying drawings which, by way of illustration, show a preferred embodiment of the present invention and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claims.

In the drawings:

Fig. 1 is a plan view of the supporting frame work and carriage structure which comprises my improved platen mechanism.

Fig. 2 is a right side elevation of the mechanism shown in Fig. 1, this view being taken from the front of Fig. 1.

Fig. 2A is a detail view of part of the mechanism shown in Fig. 2, certain parts being in another position.

Fig. 3 is an enlarged sectional detail of the hydraulic mechanism for operating the platen carriage, this view being taken substantially along the line 3—3, Fig. 1.

Fig. 4 is a front elevation of the structure shown in Figs. 1 and 2, certain parts being broken away to more clearly disclose the construction.

Fig. 5 is a front elevational view of the end plate for the platen structure, part of the elements of Fig. 4 being shown in this figure.

Fig. 6 is an elevational view of auxiliary platen mechanism, this view being taken substantially along the line 6—6, Figs. 1 and 2, and showing certain parts in section; and

Fig. 7 is a left side elevational view of the mechanism shown in Fig. 6.

The drawings show my invention applied to a printing machine of the general character disclosed in my aforesaid copending application Serial No. 416,548, now issued as Patent No. 2,410,935, and that shown in my prior Patent No. 2,296,277, issued September 22, 1942. Thus in Figs. 1 and 2 there are shown frame members 11 and 12 which correspond to frame members shown in the aforesaid copending application and patent for supporting rails along which printing members are fed to a printing station and for supporting a printing table which may comprise a relatively firm flat backing member 13 (Fig. 2) for the printing device D which comes to rest thereover at the printing station. The printing device D is of a well known type comprising one or more printing plates and other elements such as a perforated or other area affording control means for setting up devices to print and/or accumulate variable data. An example of such a device is that shown in my prior Patent No. 2,132,412 patented October 11, 1938. The device D may of course include other elements such as index cards, control tabs and the like, as well known in the art.

The platen structure which comprises the present invention includes a pair of C-shaped supports 15 and 16 which in the instant case are rigidly secured to the frame members 11 and 12 by suitable fastening means such as bolts or studs 17, 18, and 19. As shown in Fig. 4, the upper arms 20, 20A of the supports 15 and 16, respectively, project to the left and the platen structure to be described hereinafter is largely carried by such projecting arms.

On its inner face, each of the arms 20 and 20A supports an angle bracket 21 or 22 which may be welded or otherwise firmly secured thereto. Screws 23 and 24 in brackets 21 and 22, respectively, support a rigid bar 25 which abuts against the lower edges of the arms 20 and 20A, and extends above and across the printing area.

Another bar 31 extends below the bar 25 and across the same area. It is adjustably supported by the bar 25 and in spaced parallel relation therewith at three points. One support is shown at the left end of Fig. 2 and consists of a hollow adjustable abutment screw 32 and a supporting stud 33 which is threaded to and passes through

the hollow screw 32 to hold the bar 31 against the lower end of the outer screw. Near its right end, as seen in Figs. 1 and 2, the bar 31 is adjustably spaced from bar 25 by two abutment screws 35 and 36 located near the opposite edges of both bars. Midway between the abutment screws 35 and 36 there is provided a supporting stud 37 which holds the bar 31 up against the ends of said abutment screws. By adjusting these various abutment screws and supporting studs the bar 31 may be adjusted in position to tilt it either lengthwise or crosswise so as to dispose platen mechanism supported thereby in proper parallel relation with respect to the printing surface of the device D and any other printing elements supported by or in conjunction with the table surface 13.

At its ends the bar 25 supports a pair of vertical flat plates 41 and 42 secured thereto as by screws 43 and 44. These two plates serve as end frame members for supporting three shafts 45, 46, and 47 as well as certain other elements to be described hereinafter. The three shafts mentioned respectively support rollers 51, 52, and 53 for feeding paper into and through the printing position as will be described hereinbelow. The feed roller 51 is preferably separated into two parts as best shown in Fig. 1, the rear part 51A being so spaced from the front part 51 as to permit an arm 54 to be supported at an intermediate point on the shaft 45 for a purpose to be described below. A similar and parallel arm 54A is supported by the same shaft 45 at its rear end for a similar purpose. The shafts 45, 46, and 47 are held against rotation being rigidly secured to the end frame member 41 and 42 so as to serve as spacers and longitudinal frame members therewith to complete a carriage frame structure. Thus screws shown at 55, 56, and 57, Fig. 4, are used to secure the front end of the three shafts mentioned to the front end plate and, similarly, screws 58 and 59, Fig. 1, are used to secure the rear ends of the shafts to the rear plate 42.

A slideable carriage structure comprising a pair of side plates 61 and 62, held in spaced relation by a pair of bars 60, supports the platen roller which presses the article to be printed into cooperation with printing characters on the printing device or member D. Each of these side plates has its upper end bent inwardly toward the other at right angles at 61A and 62A to overlie the upper side edges of bar 31. By this construction the carriage is mounted to slide back and forth along the bar 31 which thus constitutes a guide rail for the carriage.

The carriage side plates 61 and 62 are each provided with three rollers 63 mounted in position respectively to ride in two parallel grooves 64 formed in the bottom face of the bar or guide rail 31 near its opposite edges as best shown in Fig. 4. Each of the rollers 63 is preferably mounted on its side plate 61 or 62 by means of a stud or bolt 65. Each roller is preferably provided with anti-friction bearings, for example, ball bearings, since these rollers are designed to take the thrust between the carriage and the supporting rail 31 when the platen roller is in its impression position.

The lower portion of each of the plates 61 and 62 is provided with a vertical slot 67 in which a pair of bearing blocks 68, 69 may be mounted. These bearing blocks 68 and 69 are preferably rectangular in cross section and of a width to slide freely up and down in the slots 67. A shaft

71 mounted in the bearing blocks 68 and 69 supports the platen roller 72. This roller is composed of two parts 72A and 72B as more fully described hereinafter.

The inner ends of the bearing blocks 68 and 69 are turned to form cylindrical boss portions which are slidably received in curved cam slots 74 in each of a pair of movable cam plates 76 and 77. These plates are pivotally supported on the inner faces of the plates 61 and 62 by a shaft 78 to 10 which the cam plates are rigidly secured against rotation. The shaft 78 projects through both carriage side plates and its left end, Fig. 4, shown also at the front in Figs. 1 and 2, is provided with an arm 79 which is rigidly secured to the shaft 15 78. The arm 79 carries a cam follower in the form of a flanged roller 81. The cylindrical portion of such roller 81 is adapted to contact and run along the cam shaped lower edge 82 of a plate 83 which is mounted in parallel spaced relation with the left side of the carriage, being best shown in front of the carriage in Figs. 1 and 2.

The plate 83 is secured along its upper edge to a rod or shaft 84. The shaft 84 has reduced end portions 85 and 86 which are pivotally mounted in fixed bearing blocks 87 and 88 respectively. These blocks are each rabbeted to form a flange which projects to the right, or to the rear as seen in Figs. 1 and 2, to underlie the left edge of the bar or rail 31. The block 87 is secured to bar 31 as by a screw 89 and the block 88 is similarly secured as by a screw 90.

At the rear end of the shaft 84 its reduced end portion 85 is provided with an adjustable collar 91 secured to the portion 85 in any suitable manner as by a set screw or the like. Similarly, at the front end the reduced portion 86 has another collar 92 secured thereto. These collars may be adjusted lengthwise of the shaft 84 so as to position such shaft adjustably with respect to its end supporting blocks 87 and 88. By these means the position of the cam element 92 on the lower edge of the cam plate 83 may be accurately adjusted with respect to the slidable carriage structure, so as to raise and lower the platen roller 72 at the proper times in relation to its travel.

At its lower front corner, shown at the right in Fig. 1, the cam plate 83 is provided with a tension spring 93, the other end of which is secured as to a stud 94 in block 88 to urge the cam plate clockwise or toward the carriage side plate 61. The rear end portion of the lower edge of the cam plate 83 is split from the remainder of the lower edge portion and is offset at 95 to the left, or to the front as seen in Fig. 2. When the carriage moves rearwardly the flanged cam roller 81 runs off the cam edge 82 to the right of the split portion 95. A tension spring 96 secured between an upstanding portion of the arm 79 to which the cam plates 76 and 77 are secured through shaft 78 has its other end anchored to a pin 97 mounted on the side plate 61 of the carriage. This spring tends constantly to rock the cam plates rearwardly, or clockwise as seen in Fig. 2, to the position shown in Fig. 2A. Hence, when the cam follower runs off the cam track 82 behind the offset portion 95, the plates 76 and 77 swing to the position shown in Fig. 2A and raise the platen roller out of the impression position to the tops of the slots 67 in the carriage side plates. As the carriage returns to its normal forward position the cam follower 81 runs along the inside face of the cam plate 83 until the carriage reaches its extreme forward position shown in Fig. 2A. At this point the cam edge or track 75

82 is cut away above the cam follower 81 so that the plate 83 is permitted to swing toward the carriage, under influence of spring 93, and thus dispose the cam plate in alignment with the cam follower for the next operation of the platen carriage. Hence, on the next movement to the rear, the cam follower 81 will again ride along the edge 82, being forced downwardly by such cam to the position shown in Fig. 2 as the carriage starts its movement to the rear. This of course disposes the platen roller in its operative or impression position for the rearward travel of the carriage.

With the roller in impression position, the carriage is moved to the rear by a hydraulic piston 101 mounted to slide in a hydraulic cylinder 102. The piston abuts against the forward end of the right side plate 62 of the carriage and hence when hydraulic fluid is forced through a connection 103 into the cylinder 102, the piston moves rearwardly and drives the platen roller across the printing member, until the cam follower 81 rides off the end of the cam track 82 behind the offset portion 95 as described above. A tension spring 104 is secured at one end to a stud 105 on the carriage and its other end to a lug 106 secured to the front end plate 41. This spring returns the carriage to its normal forward position as hydraulic fluid is withdrawn from the cylinder 102. The piston 101 slides through a suitable hydraulic packing 107 which is fluid tight, as well known in the art. A bleeder valve, indicated at 108, of any appropriate size and type is utilized for venting air from the hydraulic cylinder in order to maintain proper hydraulic conditions within the system, as is well known in the art. A return line 109, Fig. 3, is provided also for carrying any liquid leaking past the packing 107 back to the hydraulic supply.

For limiting the rearward stroke of the carriage there is provided a spring buffer 111 secured in the hollow head of an adjustable screw 112 which is threaded into a block 113 fastened to the lower face of the track bar 31 as by screws 114. A locking nut 115 holds the buffer 111 in desired adjusted position.

As mentioned above and as shown in Fig. 4, the platen roller 72 is preferably composed of two separable sections 72A and 72B removably secured to the shaft 71. The section 72A, shown at the left in Fig. 4, is of appropriate diameter to contact the back of the sheet or other article which is being printed by characters on the printing device D. The part 72B is smaller in diameter, constituting merely a spacer to hold the part 72A in proper alignment with the printing characters. Printing devices D utilize printing plates having various widths and when it is necessary to shift to a different type of printing device, for example one having more lines of printing characters thereon, a wider roller section 72A is employed together with a correspondingly narrower portion 72B. Hence, by the selection of appropriate pairs of roller sections, the effective widths of the platen roller may be varied as desired to cooperate with various types of printing members.

Referring to Figs. 1 and 2, it will be noted that the platen roller carriage traverses only a part of the full length of the carriage supporting structure. In printing machines of the character to which this invention is particularly applicable, it is commonly desirable to print certain data in addition to that carried by printing devices D. Such data may be variable data, for example, a date, a serial number, a numerical quantity, or

a sum of money or the like. Variable data may be set up to be printed by the employment of selectively movable variable printing members for example, numbering heads and the like. Usually such auxiliary printing members are designed to print relatively few characters and consequently the effective printing surface presented thereby is quite small as compared with the effective printing surface of printing devices D. Hence, the forces required for obtaining an adequate printing impression from such auxiliary printing elements are much less than required in taking an impression from the printing device D. Consequently the use of a roller platen is not necessary but a small reciprocating platen structure may be employed. Such a platen means is provided in the present invention for cooperating with auxiliary printing members of the type mentioned above and will next be described.

Referring to Fig. 7, the platen roller 72 and its supporting carriage structure are shown in their extreme rear positions, and the auxiliary platen mechanism is shown at the rear of the carriage and roller. The arms 54 and 54A, shown in Figs. 1 and 6, and mentioned above, are pivoted on the roller shaft 45 at their right ends as seen in Fig. 6. These arms are joined by a bar 121 extending parallel with the supporting bars 25 and 31 previously described. A platen member 122 is adjustably secured below the member 121 as by a pair of abutment screws 123 and 124 at the ends of the platen element and a supporting stud 125 at an intermediate position. By these means the bar platen 122 may be adjusted into parallel relation with respect to the printing elements (not shown) with which it cooperates.

At an intermediate part of its lower edge, located substantially midway between the ends of the platen bar 122, the bar 121 is notched to receive a plate 126 which is secured to said bar by appropriate means such as rivets or screws 127. This plate extends to the right as seen in Fig. 6, and its upper surface is tapered somewhat for cooperation with a roller 131 carried by a pair of arms 132 fixed to and depending from a short shaft 133. The shaft 133 is supported in slot in the lower face of a longitudinal bar 134, Fig. 2, which is secured at its ends to the rail member 31 by screws, or the like, 135. As shown in Fig. 1 the slot extends longitudinally to receive the shaft 133 and a pair of L-shaped brackets 136 and 137 are provided to hold the shaft 133 in the slots. These brackets are held to bar 134 by any suitable means such as screws 138.

A bell crank 141 is pivotally mounted on the rear end of the shaft 47 which supports the feed roller 53 previously mentioned. A depending arm 142 of such bell crank has attached thereto a link 143 which extends to the left as seen in Fig. 6 to connect to an arm 144 keyed to shaft 133 which also has keyed thereto the arms 132 upon which the roller 131 is mounted. The other arm of the bell crank 141 extends to the right, as shown at 145, Fig. 6, to connect to a substantially vertical link 147. A longitudinal adjustment 148 is provided for such link and its lower end 147A is attached to an arm 149. The arm 149 is rigidly secured to a hub member 151 mounted on a shaft 152 suitably supported in a pair of members 153 and 154 in the lower part of the machine. At its rear end the hub member 151 has rigidly secured thereto an offset arm 156 provided with a cam follower 157 at its end. An operating cam 161 is rotated by a shaft 162 which extends through the frame members 153 and 154 and is driven in ap-

5
10
15
20
25

propriate timed relation with other parts of the machine in an obvious manner by means not shown. Rotation of cam 161 rocks the arms 156 and 149 to move the vertical link 147 downwardly at an appropriate time in the machine cycle and thus forces the roller 131 to the left as seen in Fig. 6 over the sloping upper surface of the plate 126. This causes the platen supporting arms 54 and the platen itself to swing downwardly into impression relation with the auxiliary printing element (not shown). A tension spring 165 secured between a stud 166 projecting from the auxiliary platen and a stud 167 mounted in the bar 134 to return the platen to its normal raised position after the roller 131 is withdrawn to the right as seen in Fig. 7. A spring 171 connected between the arm 156 and a fixed element of the frame is effective to hold the cam follower 157 against its cam and to cause the roller 131 to be withdrawn to the right after an impression has been taken, thus permitting spring 165 to raise the platen 122 to its normal non-printing position.

Mention was made hereinabove of the paper guide rollers 51, 52 and 53 through which a strip or web of paper may be advanced across the printing field to take an impression from printing elements in such field. It will be understood that the primary article on which an imprint is to be taken is normally a sheet or the like which is fed over the table surface and above the printing devices D in timed relation with the feeding of such devices D. Thus as shown in Fig. 4, a sheet S to be printed may be advanced by any suitable means, such as means shown in my aforesaid Patent No. 2,296,277, to printing position. For some purposes, however, it is desirable to retain an additional copy or copies of at least part of the data, for example the variable data imprinted under the auxiliary platen mechanism described above. In such cases one or more webs W, W' may be led around the rollers 51, 52, 53 and may be advanced intermittently by suitable web feeding means, not shown, after each imprint has been taken. The means for so advancing the webs may be selected from numerous types of feeders well known in the art.

One of the webs W or W' may be a carbon coated strip to serve as an inking medium for the other. Both webs may be advanced, in cooperation with a sheet S, to a position overlying printing members and underlying one or both of the platen means described above. When the platen means presses the webs and sheet against the printing members, data is recorded on both. If desired, the imprinted web or webs may be rewound in the machine or may be severed into strips or sheets by appropriate means.

60 By comparing the platen mechanism described above with that described in my aforesaid pending application Serial No. 416,548, it will be noted that the present mechanism is lighter and requires a less complex hydraulic system. For 65 certain purposes it has marked advantages over reciprocating platens previously used in machines of the general character described hereinabove.

Hence, while I have illustrated and described the preferred embodiments of my invention, it is to be understood that these are capable of variation and modification and I therefore do not wish to be limited to the precise details set forth, but desire to avail myself of such changes and alterations as fall within the purview of the following claims.

I claim:

1. In apparatus of the character described, a pair of arms, a platen supporting framework firmly supported by said arms, a track member adjustably mounted on said framework, a roller carriage reciprocably supported by said track member, a platen roller carried by said carriage, means including a rock shaft for lowering and raising said roller to and from impression position in said carriage, means yieldingly urging said rock shaft in a direction to raise said roller, a hydraulic piston for moving said carriage through an impression stroke along said track member from an initial position to a final position, a cam plate extended parallel to said track for rocking movement about an axis parallel to said track from a normal active position to an inactive position, means yieldingly urging said cam plate to said active position, a cam follower connected to said rock shaft and engageable with said cam plate during movement of said carriage through its impression stroke to lower said roller to its impression position, means acting between said cam follower and said cam plate to shift said cam plate to its inactive position during the return stroke of said carriage, and resilient means for returning said carriage from said final position to said initial position.

2. A roller platen mechanism for a printing machine comprising a track member for reciprocably supporting a carriage, a carriage mounted on said track member, means for reciprocating said carriage, said carriage comprising a pair of side plates, a horizontal platen roller mounted for vertical sliding movement in 35

said side plates, a pair of cam followers on said platen roller adjacent opposite ends thereof, a pair of cam plates rockably mounted on said side plates having cam slots therein respectively engaging said cam followers and operable when said cam plates are rocked to raise and lower said roller, and means responsive to reciprocatory movements of said carriage for rocking said cam plates.

WALTER T. GOLLWITZER.
